(57) **CLAIM**

The ornamental design for a bottle envelope with holding means, as shown and described.

DESCRIPTION

FIG. 1 shows a perspective front view of the bottle envelope with holding means showing my new design; and, FIG. 2 shows a perspective rear view thereof.

The broken line showing of a bottle in FIGS. 1 and 2 is for illustrative purposes only and forms no part of the claimed design. The bottom and opposite side are “plain and unornamented”.
